(57) **CLAIM**

The ornamental design for a watch case, as shown and described.

DESCRIPTION

FIG. 1 is a perspective view of a watch case in accordance with the invention, in which the surfaces(s) or portion(s) of the article not shown in the drawings or described in the specification form(s) no part of the claimed design;
FIG. 2 is a front elevational view of the watch case depicted in FIG. 1;

FIG. 3 is a rear elevational view of the watch case depicted in FIG. 1;

FIG. 4 is a left side elevational view of the watch case as depicted in FIG. 1;

FIG. 5 is right side elevational view of the watch case as depicted in FIG. 1;

FIG. 6 is a bottom plan view of the watch case as depicted in FIG. 1; and,

FIG. 7 is a top plan view of the watch case as depicted in FIG. 1.
